Primary Examiner — Catherine S Posthauer(74) *Attorney, Agent, or Firm* — POLSINELLI PC(57) **CLAIM**

The ornamental design for an egg carton with dual handles, as shown and described.

DESCRIPTION

FIG. 1 is a top perspective view;

FIG. 2 is a top plan view;

FIG. 3 is a bottom plan view;

FIG. 4 is a front side view (the opposing rear view being a mirror image thereof); and,

FIG. 5 is a right side plan view (the opposing left side view being a mirror image thereof).

The dot-dash broken lines represent boundaries of the claim and form no part thereof.
